Rudolph F. Onsrud, Chicago, Ill., assignor to
Onsrud Machine Works, Inc., Chicago, Ill., a
corporation of Illinois

Application February 1, 1943, Serial No. 109,407

Term of patent 14 years

To all whom it may concern:

Be it known that I, Rudolph F. Onsrud, a citizen of the United States, residing at Chicago, in the county of Cook and State of Illinois, have invented a new, original, and ornamental Design for a Milling Machine, of which the following is a specification, reference being had to the accompanying drawings, forming part thereto.

Figure 1 is a perspective view of a milling machine showing my new design.

Fig. 2 is a front view thereof.

Fig. 3 is a back view thereof.

Fig. 4 is a top plan view thereof.

Fig. 5 is an end view thereof.

I claim:

The ornamental design for a milling machine, as shown.

RUDOLPH F. ONSRUD.
